UNITED STATES PATENT OFFICE.

ARTHUR C. BADGER, OF BOSTON, MASSACHUSETTS.

STOP-VALVE.

SPECIFICATION forming part of Letters Patent No. 762,268, dated June 14, 1904.

Application filed July 27, 1903. Serial No. 167,113. (No model.)

To all whom it may concern:

Be it known that I, ARTHUR C. BADGER, of Boston, in the county of Suffolk and State of Massachusetts, have invented certain new and useful Improvements in Stop-Valves, of which the following is a specification.

This invention relates to stop-valves; and its object is to secure lightness, ease and certainty of operation, reduction of wear, and kindred advantages.

The invention as carried out in the embodiment illustrated is applied to a device known as a "compression-cock," and includes a valve-casing and seating valve therein having a threaded body or stem engaging the casing for producing an axial opening and closing movement of the valve when the latter is rotated. Straddling the casing is a bowed operating-handle within easy reach of the fingers of an operator's hand holding the valve-casing, one end of this handle being fixed to the valve-stem to rotate the same and movable axially therewith, while the opposite end of the handle has a sliding bearing on the casing opposite the projecting valve-stem.

Of the accompanying drawings, Figure 1 represents a side elevation of a stop-valve mechanism constructed according to the present invention with the valve closed. Fig. 2 represents an end elevation. Fig. 3 represents an elevation at right angles to Fig. 1. Fig. 4 represents a longitudinal section showing the valve open. Fig. 5 represents a transverse section showing the valve closed. Fig. 6 represents a transverse section showing a modification.

The same reference characters indicate the same parts in all the figures.

In the drawings, Figs. 1 to 5, 10 is a valve-casing having inlet and outlet chambers 11 12, separated by a partition which is formed with an aperture surrounded by a valve-seat 13. 14 is the rotatable and axially-movable valve adapted to open and close against said seat and having its stem or body formed with a quick-pitch screw-thread 15, engaging a complementary thread 16, formed within a branch of the casing, which is closed by a screw-cap 17. The reduced part 18 of the valve-stem passes through a stuffing-box 19 in

this cap and outside of the casing is formed with a polygonal or flat-sided portion 20, with which is connected one end of a bowed operating handle or bail 21, straddling the casing. A rigid connection between the valve-stem 55 and the handle is thus formed, whereby when the handle is rotated or oscillated by the operator's fingers the valve is also rotated because of the screw-thread and caused to open and close against its seat by an axial 60 movement. The opposite end of the handle 21 is provided with a bearing on a cylindrical stud 22, screwed on an integral stem 23, which is formed on the casing in line with the axis of the valve. This end of the handle is 65 mounted for an axial sliding movement on the stud 22, which permits the axial movement of the handle required by the opening and closing movement of the valve. It will be observed that the handle 21 is brought 70 within convenient reach of the thumb or fingers of the operator's hand holding the valve-casing 10, so that this form of apparatus permits the operator to handle and direct the valve-casing and operate the valve thereof 75 with one hand. At the same time the handle is adequately supported, giving an easy movement thereof with a minimum of friction and reducing wear and strain on the valve and its stem and because of such construction permitting the parts to be made relatively light 80 without sacrificing strength or durability.

Modifications may be made without departing from the idea of means contained in the described construction. For instance, the location of the screw-thread may be changed or equivalent devices giving the same effect may be substituted therefor. In Fig. 6, for example, I have shown the valve-stem as having a smooth bearing 24 within the casing and the 85 stud 22 and operating-handle 21 as having complementary threads 25 26 formed thereon for producing the desired axial movement of the valve when the handle is rotated.

I claim—

1. In a stop-valve mechanism, a casing, an axially-movable seating valve therein having a stem projecting outside the casing, and a bail straddling the casing, one of its ends having a bearing on the casing opposite the pro- 100

- jecting stem, the other end being engaged with the stem, and means whereby a rotary movement of said bail imparts an axial movement to the valve.
5. 2. In a stop-valve mechanism, a casing, a seating valve therein opening and closing by an axial movement, coöperating threaded members on the valve structure and casing respectively for producing such movement by 10. their relative rotation, and a bail for producing such relative rotation, the same straddling the casing and having one end connected to the valve structure, its other end having a bearing on the opposite side of the casing from 15 such point of connection.
3. In a stop-valve mechanism, a valve-casing, a rotatable and axially-movable operating-handle having a sliding bearing at one end on the casing, and a valve in the casing
- connected with the other end of the handle for 20 operation thereby.
4. In a stop-valve mechanism, a casing, a valve therein opening and closing by an axial movement, coöperating screw-threaded members for producing said axial movement, one 25 of which has a projection outside of the casing, and an axially-movable bail having one end connected to rotate said projection and move axially therewith, the other end having a sliding bearing on the casing opposite said 30 projection.
- In testimony whereof I have affixed my signature in presence of two witnesses.

ARTHUR C. BADGER.
